(57) **CLAIM**

The ornamental design for a toothbrush caddy, as shown and described.

DESCRIPTION

FIG. 1 is a perspective front view of a toothbrush caddy, showing my new design;

FIG. 2 is a front view thereof;

FIG. 3 is a rear view thereof;

FIG. 4 is a right side view thereof;

FIG. 5 is a top view thereof;

FIG. 6 is a bottom view thereof; and,

FIG. 7 is a perspective view of the toothbrush caddy with the drawer in an open configuration.

The left side view is identical and opposite of the right hand side view of FIG. 4.
